Primary Examiner — Catherine Ho

(57) **CLAIM**

The ornamental design for a label, as shown and described.

DESCRIPTION

FIG. 1 is a front view of the first embodiment for a label, showing our new design; and
FIG. 2 is a back view thereof;

FIG. 3 is a front view of the second embodiment for a label;
FIG. 4 is a front view of the third embodiment for a label;
and,

FIG. 5 is a front view of the fourth embodiment for a label. The broken line portion of the figure drawings is included to show portions of the article that forms no part of the claimed design. The Dot-Dash broken lines define the bounds of the claimed design and form no part thereof.

1 Claim, 5 Drawing Sheets
